Hanson & Hanson*

UNITED STATES PATENT OFFICE.

CLARENCE V. ROBERTS, OF PHILADELPHIA, PENNSYLVANIA, ASSIGNOR TO ROBERTS & MANDER STOVE COMPANY, OF PHILADELPHIA, PENNSYLVANIA, A CORPORATION OF PENNSYLVANIA.

DESIGN FOR A GAS-HEATER.

53,048.

Specification for Design.

Patented Mar. 4, 1919.

Application filed December 18, 1918. Serial No. 267,414. Term of patent 7 years.

To all whom it may concern:

Be it known that I, CLARENCE V. ROBERTS, a citizen of the United States, residing in Philadelphia, Pennsylvania, have invented a certain new, original, and ornamental Design for a Gas-Heater, of which the following is a specification, reference being had to the accompanying drawing, forming part

thereof, in which the figure is a perspective view of a gas-heater illustrating my new design.

I claim:—

The ornamental design for a gas heater, substantially as shown.

CLARENCE V. ROBERTS.
